(74) *Attorney, Agent, or Firm* — Sterne, Kessler, Goldstein & Fox PLLC

CLAIM

The ornamental design for a graphical user interface for a display screen or a portion thereof, as shown and described.

DESCRIPTION

FIG. 1 is a front view of a graphical user interface for a display screen or portion thereof showing our new design; and, FIG. 2 is a front view of a second embodiment thereof. The broken line showing of the display screen or portion thereof forms no part of the claimed design.
